(57) **CLAIM**

The ornamental design for a trim panel, as shown and described.

DESCRIPTION

FIG. 1 is a front, top, right axonometric view of a trim panel showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front axonometric view of the trim panel shown in a reference view of usage;

FIG. 9 is a rear, bottom, left side axonometric view thereof; and,

FIG. 10 is a perspective view of the trim panel of FIG. 1, shown in a state of use with additional environmental subject matter.

The broken lines in FIG. 10 that show a keyboard dock depict environmental subject matter and form no part of the claimed design. All other broken lines seen in the drawings depict portions of the trim panel that form no part of the claimed design.

1 Claim, 8 Drawing Sheets
